UNITED STATES PATENT OFFICE

EMILE RIMAILHO, OF PARIS, FRANCE

ELASTIC WHEEL WITH FLEXIBLE RIM

Application filed May 13, 1927, Serial No. 191,200, and in France May 25, 1926.

It has already been proposed to employ the two circles O and O' whose radius is the radius of curvature at the ends of the large horizontal axis, said circles being connected together by the lines $a b$, $a' b'$ at the top and bottom. The form is chiefly defined by the spacing between the sides 5 and 6, in order to fix the radius of the circles O and O' , for the sinking will cease when 5 and 6 are in contact. In like manner, the spacing between the sides 3 and 4 will define the lines $a b$, $a' b'$ whose descent will cease when 3 and 4 are in contact. In this manner I may already limit the maximum deformation of the wheel rim by the proper choice of the inclination of the sides 3 and 4 and the sides 5 and 6. A second method of reacting against the descent of the wheel rim which is thus formed is shown in Fig. 3, and herein I place elastic elements between the sides 3 and 4 which act in an elastic manner to prevent the sides from coming together. The action of such elastic elements will be the optimum when the spring 7 tends to separate 3 from 4, and the spring 8 will tend to approach 5 from 6 at the same time, or vice versa.

10 The present invention has for its object to provide a wheel of this class in which the rim is constituted by circular flexible strips, these strips supporting bearing pieces to which are secured the india-rubber rings connecting the rim to the middle of the wheel, these bearing pieces being provided with stops disposed upon the circumference so as to maintain the said pieces apart, these pieces pressing between them india-rubber blocks 15 acting as interposed elastic elements and as tread segments.

15 20

A flexible wheel rim in accordance with the invention will not remain exactly circular, and when it has the proper dimensions it will become elliptical under a load applied to the hub, and will become locally flattened or otherwise distorted when in contact with an obstacle.

In the said device, the outer rigid circular element or rim is eliminated, and I thus obviate all rolling stress upon the elastic tyre which is usually mounted on the said rigid wheel rim. I also facilitate the use of removable elements for the rolling portion, and these can be renewed after wear, and are securely held in place in order to withstand the centrifugal action and to provide for operation at high speeds.

The diagrammatic views which are shown in Figs. 1 and 2 represent the form of the said tyres, by which the functioning will be understood. The wheel rim herein consists of the links 1 which are connected together by the pivots 2 and comprise the sides 3 and 4 which are reduced towards the exterior, and the sides 5 and 6 which are reduced towards the interior. As shown in Fig. 2, the said wheel rim rests upon the ground $a b$ and is flattened by its own weight. It is observed that the form thus assumed will be represented by

Fig. 5 shows that the individual pivots 2 may be replaced by a continuous flexible band 17 upon which are mounted the blocks 1. The band 17 may perform by its own elasticity the function of the springs 7 and 8 shown in Fig. 3.

Figs. 1, 2, 3, 4 and 5 illustrate the preceding theoretical data.

Figs. 6 to 9 relate to a construction according to the invention in which the core of the flexible rim consists of spring steel hoops, in which views

Fig. 6 is a partial front view of the wheel with parts broken away in section.

Fig. 7 is a cross section of the same according to line VII—VII of the Fig. 6.

5 Figs. 8 and 9 are fragmental circumferential sectional views according to lines VIII—VIII and IX—IX respectively of the Fig. 7.

10 In Figs. 6 to 9, the flexible rim comprises two circular elastic metallic strips 17 and 18 upon which are mounted bearing pieces 19, each of which comprises a plate 20 in contact with the exterior of said strips.

15 Inside of these strips, each piece 19 comprises two arms 21 disposed perpendicularly to the plane of the wheel and forming axles to which are hooked two tension rings 34 preferably of rubber; said rings preferably converge two by two towards the interior of the wheel whereby it will be better strengthened. The tension rings on the other hand are hooked to axles 12 integral with pieces 13 which are maintained on the two sides of the web 29 of the wheel by axles 14.

20 25 Each piece 19 further comprises, on both sides of its middle part, in the plane of the wheel, an extension 22 which is disposed between the metallic strips.

30 Said extensions 22 make two by two mutual contact at 23.

Between the bearing pieces 19 are disposed india-rubber blocks 15, by example, maintained by hoops 16.

35 A strap 26 embraces each piece 19, surrounding the hoops 16 and its ends are attached to arms 21.

40 Each piece 19 further comprises, inside the strips 17 and 18, an end part 27 provided with an india-rubber buffer 28 adapted to make contact with pieces 13, either when the deformation of the elastic wheel rim is excessive or when the eccentricity of the hub is too great.

Having thus described my apparatus, what 45 I claim as new therein, and my own invention, is:

1. In an elastic wheel, the combination of an internal rigid circular element, an external flexible rim, elastic members subjected to tension connecting the said rigid circular element with the said flexible rim, this rim being constituted by at least one circular flexible strip, bearing pieces carried by the strips and to which are attached the said elastic members, these bearing pieces being provided with stops disposed upon the circumference so as to maintain the said pieces apart, india rubber blocks pressed between these pieces and acting as interposed elastic elements and as removable tread segments.

2. In an elastic wheel, the combination of an internal rigid circular element, an external flexible rim, elastic members subjected to tension connecting the said rigid circular element with the said flexible rim, this rim be-

ing constituted by two circular flexible strips having between them an interval, bearing pieces maintained in these intervals and to which the said elastic members are attached, these bearing pieces being provided with stops, disposed upon the circumference so as to maintain the said pieces apart, india rubber blocks pressed by these pieces and acting as interposed elastic elements and as removable tread segments.

3. In an elastic wheel, the combination of an internal rigid circular element, an external flexible rim, elastic members subjected to tension connecting the said rigid circular element with the said flexible rim, the said rim being constituted by at least one circular flexible strip, bearing pieces carried by these strips and to which the said elastic members are attached, these bearing pieces being provided with stops disposed upon the circumference so as to maintain the said pieces apart, india rubber blocks pressed by these pieces and acting as removable tread segments, and the parts of these pieces which are nearest to the center carrying stops which limit the deformation of the rim in the direction in which this deformation increases the radius of curvature of the said rim.

In testimony whereof I have hereunto affixed my signature.

EMILE RIMAILHO.
